D23-346

EX

D7463

OR D 6,958

UNITED STATES PATENT OFFICE.

JOHN MARTINO, OF PHILADELPHIA, PENNSYLVANIA, ASSIGNOR TO
CHARLES NOBLE & CO., OF SAME PLACE.

DESIGN FOR A STOVE.

Specification forming part of Design No. 6,958, dated October 14, 1873; application filed August 16, 1873.
[Term of Patent 3½ years.]

To all whom it may concern:

Be it known that I, JOHN MARTINO, of Philadelphia, Pennsylvania, have invented a Design for Stove, of which the following is a specification:

The nature of my design is fully set forth by the accompanying photographic illustration, to which reference is made.

It should be remarked in the outset that the central illuminated portion A of the stove is not included in my present design, as it furnished the subject of a former patent, my design being limited to the lower portion B and top D of the stove.

The lower portion consists of a base, a, surmounted by a ring, b. The base a has two hinged doors, in the center of each of which is a register, the latter being surrounded by a circular beading, between which and the beaded outline of the door are scroll-like ornaments. The base a at either side of and above the doors is ornamented by beads and foliated ornaments of a character so clearly shown in the drawing as to require no minute description. The ring b above the base is of the form of the frustum of a cone, has a lower flange or bead, c, ornamented mica mounted panels i and leaf-like ornaments f between the panels.

The top D of the stove consists of a cap, d, surmounted by an urn, e. The cap is orna-

namented by circular rows of beading, some of which are plain, some scalloped, and others foliated. The urn e is open-work, its lower portion being composed of a series of ornamented curved ribs, and the upper portion has a scalloped edging, a circular row of oval ornaments above the same, and a projecting ornament at the extreme top, of the character clearly shown in the drawing.

I claim—

1. The design for the ornamented base a of the stove and its doors, as described and represented.
2. The design for the illuminating-ring b, with its panels and ornaments, as described and represented.
3. The design for the whole lower portion of the stove, consisting of the base a and ring b, as shown and described.
4. The design for the top of the stove, including the cap d and urn e, ornamented as described, and as represented in the drawing.

In testimony whereof I have signed my name to this specification in the presence of two subscribing witnesses.

JOHN MARTINO.
